SPINNING AND TWISTER FRAME

Gordon C. Anderson, Saco, Maine, assignor to
 Saco-Lowell Shops, Boston, Mass., a corpora-
 tion of Maine

Application April 3, 1940, Serial No. 327,598

2 Claims. (Cl. 242—43.3)

This invention relates to the builder motions of spinning and twister frames, both being hereinafter included in the term "spinning frame."

A typical mechanism of this character includes a series of lifter rods located at spaced intervals along the side of the frame and supporting the traversing ring rail on their upper ends. Associated with each of these rods is a lifter arm, customarily counter-weighted, and the entire series of arms is connected with a lever operated by a builder cam at the head of the frame. In some arrangements the weight of the ring rail is dependent upon to produce its lowering movement under the control of the builder cam and its connections with the lifter rods, while the power of the cam is utilized to lift the rail. In others the cam produces the lowering movement and counter-balancing weights are utilized to lift the rail.

While these mechanisms have long been used and they do work well in the great majority of cases, nevertheless they require considerable attention and they are subject to periods of hesitation and non-uniformity of movement arising from a multiplicity of causes.

The present invention aims to devise a lifter mechanism in which the forces utilized to lift the ring rail will be controlled more accurately and those which must be overcome by the cam in lowering the rail will be more uniform, to the end that a smoother and more accurately controlled movement of the ring rail will be produced.

The nature of the invention will be readily understood from the following description when read in connection with the accompanying drawings, and the novel features will be particularly pointed out in the appended claims.

In the drawings,

Figure 1 is a side elevation of those parts of a builder mechanism with which this invention is more especially concerned and illustrates an arrangement embodying the invention;

Fig. 2 is a diagrammatic view showing the manner in which the mechanism shown in Fig. 1 may be connected with the cam driven lever at the head of the frame; and

Fig. 3 is a view similar to Fig. 1 showing another embodiment of the invention.

Referring first to Fig. 1, a portion of a ring rail is shown at 2 carrying a series of rings 3, each mounted in cooperative relationship to a spindle 4, which, in turn, is supported in a box rail or spindle rail 5. The ring rail is mounted on the upper end of a series of lifter rods, one of which is shown at 6, this rod being supported

for vertical reciprocating movement in guides 7—7 of a bracket 8 which is secured to the spindle rail. So far as these features are concerned, the construction illustrated is like those in common use.

According to the present invention, a lifter arm 10 is mounted to swing on a pivot 12 supported in the bracket 13, and it carries a roll at its outer end bearing against the lower surface of a bracket 14 secured fast to the lifter rod 6. For the purpose of operating the arm 10, another arm 15 is mounted on the pivot 12, or is pivotally supported co-axially with it, and it is also pivoted at 16 to the connecting rod 17 which transmits the pull of the builder cam to the arm. A thrust screw 18 is threaded through the arm 10 and bears at its lower end on the arm 15 so that the part of the weight of the ring rail borne by the lifter rod 6 is transmitted through the arm 10 and screw 18 to the arm 15. The force so exerted on the latter arm is opposed by the lifter spring 20, one end of which is connected to the arm 15 at 21, while its opposite end is adjustably anchored to the bracket 22.

Fig. 2 shows diagrammatically two of these lifter mechanisms connected to a ring rail and also to the usual heart-shaped builder cam 23 acting on the roll 24 of the builder arm 25, the latter being connected by a chain 26 to the rod 17 through a bell crank lever, one arm 27 of which is fastened to the chain while the other arm 28 is pivoted to the right-hand end of the connecting rod 17.

It should be observed that in the arrangement shown in Fig. 1 the parts 10 and 15 form, in effect, the work arm and power arm, respectively, of a bell crank lever through which the force applied by the spring 20 is transmitted. The entire series of springs associated with the respective lifter rods of the complete set supporting the ring rail thus is utilized to raise the rail. The lowering movement of the rail is produced by the cam 23 operating through the connections just described between this element and the arms 15, it being understood that the point of this cam is down when the lifter rods are at the lower limit of their stroke. At this time the lifter arms 10 are inclined downwardly. During all of this lowering movement energy is being stored in the spring. The springs 20 act at all times to hold the roll 24 firmly against the edge face of the cam 23, the cam overcoming the combined action of the springs during the lowering movement of the rail and also controlling the rise of the rail which is produced solely by said springs.

It is important to the production of a uniform rate of rise or fall of the rail that the lifting effort exerted by the springs 20 on the respective lifter rods 6 associated therewith should be substantially constant throughout the entire range of travel of the rail, and an important novel feature of this invention consists in so relating the springs to the parts which they operate that this result will be produced.

Referring again to Fig. 1, it will be observed that the ring rail is there shown at the upper limit of its travel. Consequently, at this time the cam roll is passing the low point of the cam and will next be moved downward gradually by the rise of the cam. This movement will be transmitted by the connections above described to the arm 15 to swing this arm in a counter-clockwise direction around the pivot stud 12. It will also be noted that the point of connection 21 of the spring with the lever arm 15 is about 30° to the right of the vertical plane through the axis 12, and that as the movement just described continues, the point 21 swings upwardly in an arc struck about the axis of the pivot 12. This arrangement is such that as the tension of the spring 20 increases, the effective leverage which it exerts on the arm 15 becomes shorter, with the result that it exerts a substantially constant torque on said arm in a direction tending to make it rotate around said axis to lift the rod 6. Assuming, for example, that the spring in its shortened position, as shown in Fig. 1, exerts a pull of one hundred pounds and that its effective leverage is eight inches, while in its extended position it pulls one hundred sixty pounds and its effective leverage is reduced to five inches, then the torque produced in the two positions would be equal. That exerted in the intermediate positions of the arm would not vary materially from the same value.

The tension of the spring 20 may be adjusted by either of its connections with the bracket 22 or the arm 15, most of the adjustment, however, preferably being made at the former. For this purpose the left-hand end, Fig. 1, of the spring is secured to a tapered head on the bolt 30 on which a nut 31 and a check nut 32 are threaded. The former has a rounded head bearing in a concave socket in the end of the bracket to permit the bolt to remain in the axis of the spring as the latter swings. The connection at the opposite end of the spring includes a hook extending over a stud which projects laterally from the head of a bolt 33 extending loosely through a hole in a lug or flange 34 forming part of the arm 15. An adjusting nut and a check nut are threaded on the bolt at the right-hand side of the part 34. The angular relationship of the two arms 10 and 15 may be adjusted by means of the bolt 18.

This arrangement has been found in practice to operate very smoothly and its connections with the cam mechanism can readily be made such that all of the cross-shafts commonly provided in a mechanism of this character, with the possible exception of that nearest the cam mechanism, may be eliminated. These cross shafts and their bearings are a substantial cause of annoyance and are partly responsible for the unsatisfactory operation of builder motions of the type commonly used.

Another form of the invention is illustrated in Fig. 3, differing chiefly from that shown in Fig. 1 in that a compression spring is used instead of a tension spring. The parts corresponding to those illustrated in Fig. 1 are designated by the

same, but primed, numerals. In this arrangement the outer or right-hand end of the compression spring 35 bears against the disk-like end 36 of a housing or shell 37, and the latter is held in a relatively stationary position by means of a rod 39, the left-hand end of which extends through, and is adjustably anchored in, a lug 40 projecting from the stationary bracket 13'. The thrust of the spring 35 is transmitted to the lever arm 15' through a semi-spherical member 41, slideable on the rod 39, and carried by a housing member 42 which telescopes within the corresponding member 37. A concave socket is formed in the end of the extension b of the arm 15' to serve as a seat for the member 41.

In this construction the spring 35 is related to the arm 15' in essentially the same manner as in the embodiment of the invention shown in Fig. 1. The angle at which it operates on the lever, and the point of application of its pressure thereto, bear essentially the same relation to the pivot 12' as does the spring 20 in the construction previously described. The spring also can be adjusted in much the same manner. In both arrangements the springs are disposed approximately horizontally at one end of the range of travel of the ring rail and the angle through which they operate is nearly the same. The construction shown in Fig. 3, however, has the advantage of being somewhat more compact and the spring is protected from dust and fly. It will be observed that the extension b of the lever arm 15' has a tapered internal space through which the rod 39 extends and which is so shaped as to clear the rod during the swing of the lever.

While the arms 10 and 10' in these two constructions, and the load which they carry, do not exert exactly the same torque about the pivot on which the lifter arm swings throughout the entire range of travel of the ring rail, the variation in this force is not sufficient to interfere materially with the operation above described. The adjustment preferably is made such that the arms swing through equal arcs above and below a mean horizontal position, and the total departure from this position is not great. Consequently, the application of a uniform torque around the axis 12 by the spring 20, or the spring 35 in the form shown in Fig. 3, produces a substantially uniform lift on the ring rail throughout its entire range of travel. The maximum error so introduced is only about 3% or 4%.

While I have herein shown and described a typical embodiment of my invention, it will be evident that the invention is susceptible of embodiment in other forms without departing from the spirit or scope thereof.

Having thus described my invention, what I desire to claim as new is:

1. In a spinning frame including a ring rail and a series of lifter rods supporting it, mechanism for reciprocating said rail vertically including a pivoted lifter arm associated with each rod, a power arm movable about the pivot of each lifter arm in unison with the latter and connected therewith to operate it, and a compression spring connected with each power arm to act on it in a direction tending to lift said rail, each lifter arm being mounted to swing through an arc having approximately equal portions above and below a middle horizontal position, a tension rod connecting said spring with a stationary part of the machine, each spring having a rocking connection with its respective power arm and

each rod having a similar connection with said stationary part of the machine to accommodate the swinging movement of the rod during the traversing movement of said rail.

2. In a spinning frame including a ring rail and a series of lifter rods supporting it, mechanism for reciprocating said rail vertically, comprising a series of pivoted lifter arms each supporting a lifter rod on its outer end, a power arm associated with each lifter arm and mounted to swing about the same axis as the lifter arm and connected therewith to operate the latter, each power arm extending downwardly from its pivotal support, a thrust screw connection between each of said power arms and its cooperating lifter

5 arm adjustable to vary the relationship between said arms, links connecting the lower portions of adjacent power arms together, and a series of springs connected with the respective power arms and acting on them in a direction tending to lift said rail, said springs extending lengthwise of the frame and each spring being so related to its respective power arm that as its tension changes with the rising and falling movements of said ring rail, the effective leverage exerted by the springs will change inversely to such a degree as to produce an approximately uniform lifting effort on the ring rail throughout its range of travel.
